UNITED STATES PATENT OFFICE

HOWARD E. CROCKER, OF MALDEN, AND WINFRED W. HARRIS, OF MELROSE,
MASSACHUSETTS; SAID HARRIS ASSIGNOR TO SAID CROCKER

WASHING MACHINE

Application filed July 20, 1931. Serial No. 551,832.

This invention relates to a washing machine for domestic purposes and particularly designed for use in connection with the ordinary set laundry tubs.

5 It is the general object of our invention to provide a washing machine of the vertically reciprocated suction cup type, so designed that the washing mechanism may be readily mounted above a set-tub and operated there-
10 in, and that it may be easily removed there-
from when the machine is not in use.

A further object is to provide a motor drive for such a washing mechanism and a support or standard for the motor which may
15 be conveniently positioned and secured at the side of a set-tub, and on which standard the frame of the washing mechanism is detach-
ably supported.

20 We have also provided improved means for shifting the angular operative position of the suction cups between successive vertical movements thereof.

Our invention further relates to arrangements and combinations of parts which will
25 be hereinafter described and more particu-
larly pointed out in the appended claims.

A preferred form of the invention is shown in the drawings, in which

Fig. 1 is a plan view of our improved
30 washing machine;

Fig. 2 is a front elevation thereof, with the tub shown in section along the line 2—2 in Fig. 1;

Fig. 3 is a side elevation of certain detail parts, looking in the direction of the arrow 35 3 in Fig. 2;

Fig. 4 is a detail sectional elevation, taken along the line 4—4 in Fig. 2;

Fig. 5 and 6 are detail sectional plan 40 views, taken along the lines 5—5 and 6—6 in Fig. 2 respectively;

Fig. 7 is a plan view of certain mechanism for moving the cups angularly;

Fig. 8 is a partial side elevation of an in-
45 terrupted bevel gear, and

Fig. 9 is a detail sectional elevation, taken along the line 9—9 in Fig. 1.

50 Referring particularly to Fig. 2, our improved washing machine comprises a wash-
ing mechanism assembled upon a frame 10

having a base portion 11 slidable in guideways 12 formed on a platform 13 secured to the upper end of a post or standard 14. The standard 14 is provided with an extended base 15 adapted to rest on the floor or
55 other suitable surface.

The post 14 is vertically adjusted in the base 15 so that the under side of the platform 13 will rest upon the upper edge of the side wall of a set-tub T, being preferably separated therefrom by a layer of cushion material 16. The post 14 may be secured in vertically adjusted position by a set-screw 17 and is provided with an arm 18 vertically slidable on the post and projecting under
60 65 the tub T. After the post or standard is placed in position, the arm 18 is moved upward to firmly engage the under side of the tub T and may be secured in adjusted position by a clamping lever 20 (Fig. 6).
70

The base portion 11 of the frame 10 is provided with a latch or locking lever 22 (Figs. 2 and 9) adapted to be received in a recess between lugs or projections 23 on top of one of the guideways 12, thus preventing displacement of the washing mechanism during
75 the operation thereof.

A motor M is mounted on the platform 13 and is provided with a driving pulley 25 connected by a belt 26 (Figs. 1 and 2) to a 80 pulley 27 forming a part of the washing mechanism. When it is desired to remove the washing mechanism from operative position, it is merely necessary to slip the belt 26 off of the pulleys 25 and 27 and to swing the latch or locking lever 22 to upright position. The entire washing mechanism and its supporting frame may then be removed and placed in storage until again needed.
85

The pulley 27 is mounted on a short shaft 90 30 (Fig. 2) rotatable in a fixed bearing in the frame 10 and provided with a pinion 31 engaging a gear 32 mounted on a short shaft 33, also supported in a fixed bearing in the frame 10.
95

A crank-pin 35 is mounted in the outer side of the gear 32 and extends through a slot 37 (Fig. 2) in a lever 38, pivoted at 39 to the frame 10. The outer end of the lever 38 is forked, as indicated at 40 in Fig. 1, to receive
100

a block 42 provided with bearing studs 43 which extend outward through slots 44 (Fig. 2) in the forked ends 40 of the lever 38.

The block 42 is formed in two separate parts, suitably secured together and having a spherical recess in their inner faces adapted to receive the ball-shaped upper end 46 (Fig. 3) of a plunger 47. The plunger 47 is slidably mounted in a tubular member 48 (Fig. 2) and is provided with a cross-pin 49 projecting outward through slots 50 in the member 48.

A spring 52 is enclosed within the member 48 and normally forces the plunger 47 upward until the cross-pin 49 engages the upper ends of the slots 50, as shown in Fig. 2.

The lower end of the spring 52 rests upon the top of a plug 54, secured in the lower end of the tubular member 48 by a cross-pin 55. A collar 60 is secured to the lower end of the plug 54 by a cross-pin 61 (Fig. 5) and is provided with three equally spaced vertical openings 62 and with radial slots 63 in the bottom surface of the collar which extend in 25 as far as the openings 62.

Suction cups 65 are mounted on slightly resilient arms 66 having up-turned ends 67 adapted to be positioned in the openings 62 and to be secured therein by cross-pins 68. When thus positioned, the arms 66 extend 30 outward through the slots 63 and are thus held in desired angular relation.

The tubular member 48 is slidable in a sleeve 70 (Fig. 7) but is held from relative angular movement therein by a key 71. The sleeve 70 is rotatably mounted in a bearing 72 supported by the frame 10, and the sleeve 70 is provided with an arm 74 connected by a link 75 to a crank-pin 76 on a crank arm 40 77 secured to the lower end of a short upright shaft 78 (Fig. 2) rotatable in a bearing 79 in the frame 10.

An interrupted bevel pinion 80 is secured to the upper end of the shaft 78 and is engaged by an interrupted bevel gear 82, mounted on the shaft 33 previously described and rotatable with the gear 32 by which the suction cups 65 are vertically reciprocated.

The bevel gears 80 and 82 cooperate to provide a Geneva motion by which the bevel pinion 80 and crank arm 77 are given successive angular movements of 180° each, with intervening periods of rest. By such movements, the arm 74 is moved alternately from 55 the position shown in full lines in Fig. 1 to the position shown in dotted lines in the same figure.

On one revolution of the bevel gear 82 the arm 74 will be moved to one position and on 60 the next revolution of the gear 82 the arm will be moved to its opposite position, thus occupying its two positions alternately on successive vertical movements of the cups.

Having described the details of construction of our improved washing machine, the

method of operation and advantages thereof will be readily apparent.

Assuming that the machine has been placed in operative position with reference to the tub T and that a load of clothes have been placed in the tub, the motor M is then started and revolves the gear 32 at relatively slow speed, due to the double reduction between the pulleys 25 and 27 and between the pinion 31 and gear 32.

As the gear 32 rotates, the crank-pin 35 swings the lever 38 about its fixed pivot and moves the plunger 47 and tubular member 48 vertically in the sleeve 70, thus vertically reciprocating the suction cups 65. If the load is too heavy, the spring 52 yields and allows the plunger 47 and tubular member to telescope.

At every revolution of the gear 32, the associated bevel pinion 82 gives the bevel pinion 80 a half revolution, thus changing the angular position of the cups 65. Preferably this change in position takes place during the first part of the downward movement of the cups, thus producing a spreading or shifting action on the clothes before the direct downward movement of the cups becomes effective. The washing of the clothes is thus accomplished in a very satisfactory manner. When the washing is completed the washing mechanism may be quickly removed by releasing the locking lever 22 and throwing off the belt 26.

Having thus described our invention and the advantages thereof, we do not wish to be limited to the details herein disclosed, otherwise than as set forth in the claims, but what we claim is:—

1. In a washing machine for use with a set-tub, a plurality of suction cups, a vertically reciprocated member supporting said cups, a sleeve in which said member is slid- 105 able but relatively non-rotatable, means including a crank disc effective to reciprocate said member, and means including a crank driven by said crank disc to move said sleeve angularly.

2. In a washing machine for use with a set-tub, a plurality of suction cups, a vertically reciprocated member supporting said cups, a sleeve in which said member is slid- 115 able but relatively non-rotatable, means including a crank disc effective to reciprocate said member, and means including a crank driven by said crank disc to move said sleeve angularly and alternately to one or the other of two operative positions, and to hold said sleeve at rest for a substantial period of time after each such motion.

3. In a washing machine for use with a set-tub, a plurality of suction cups, a vertically reciprocated member supporting said cups, a sleeve in which said member is slid- 125 able but relatively non-rotatable, means to reciprocate said member, and means to move said sleeve 130

angularly and alternately to one or the other of two operative positions, said latter means comprising an intermittent gear and an intermittent pinion which cooperate to effect 5 a Geneva motion.

4. In a washing machine for use with a set-tub, a plurality of suction cups, a vertically reciprocated member supporting said cups, a sleeve in which said member is slid- 10 able but relatively non-rotatable, means to reciprocate said member, and means to move said sleeve angularly and alternately to one or the other of two operative positions, said latter means comprising an intermittent bevel 15 gear and an intermittent bevel pinion which cooperate to give said pinion successive half revolutions with intervening periods of rest.

5. In a washing machine, a plurality of 20 suction cups, a vertically reciprocated member supporting said cups, said member having a ball-shaped upper end, an actuating lever having a forked end, means to swing said lever in a vertical plane and a block slid- 25 able in said forked end and having a pin and slot connection therewith, said block having also a swivel connection to the ball-shaped end of said reciprocated member.

6. In a washing machine, a vertically re- 30 ciprocated member, a collar secured thereto and having angularly spaced openings extending parallel to the axis of said collar and having radial slots in one end connecting with said openings, a plurality of suc- 35 tion cups, arms for said cups having up- turned ends, said arms being seated in said openings and radial slots, and means to secure said arms in said openings.

7. In a washing machine for use with a 40 set-tub, a motor, a standard supporting said motor, means to position and secure said standard with respect to said tub, a washing unit comprising an agitator and a transmission mechanism for actuating the agitator, a 45 supporting frame for said unit, a platform adjacent the top of said standard, having an extending portion, means to slidably mount said supporting frame on said extending portion whereby said unit is movably 50 mounted on the standard, and means to detachably secure said frame, platform and standard in assembled relation.

8. In a washing machine for use with a 55 set-tub, a motor, a standard supporting said motor, means to position and secure said standard with respect to said tub, a washing unit comprising an agitator and a transmission mechanism for actuating the agitator, a supporting frame for said unit, having 60 guides thereon, a platform adjacent the top of said standard, having an extending portion, guideways on said extending portion engageable with the guides on said frame whereby to slidably mount said frame on said 65 platform, and a locking lever to detachably

secure said frame to said platform and standard.

9. In a washing machine for use with a set-tub, a motor, a standard supporting said motor, means to position and secure said standard with respect to said tub, a washing unit comprising an agitator and a transmission mechanism for actuating the agitator, a supporting frame for said unit, a platform adjacent the top of said standard, having an 70 extending portion, means to slidably mount said supporting frame on said extending portion whereby said unit is movably mounted on the standard, and means to detachably secure said frame, platform and standard in as- 75 sembled relation, and a readily detachable driving connection between said motor and said transmission mechanism, including pul-leys and a readily removable belt.

10. In a washing machine for use with a set-tub, a motor, a standard supporting said motor, means to position and secure said standard with respect to said tub, a washing unit comprising an agitator and a transmission mechanism for actuating the agitator, a 80 supporting frame for said unit having guides thereon, a platform adjacent the top of said standard, having a portion extending substantially horizontally and adapted for projection over the set tub, guideways on said 85 extending portion engageable with the guides on said frame whereby to slidably mount said frame on said platform, for movement into position over the set tub, and a locking lever to detachably secure said frame to said plat- 90 form and standard.

11. In a washing machine for use with a set-tub, a motor, a standard supporting said motor, means to position and secure said standard with respect to said tub, a washing unit comprising an agitator and a transmission mechanism for actuating the agitator, a supporting frame for said unit, a platform adjacent the top of said standard, having an 100 extending portion, means to slidably mount said supporting frame on said extending portion whereby said unit is movably mounted on the standard, and means to detachably secure said frame, platform and standard in as- 105 sembled relation, and a readily detachable driving connection between said motor and said transmission mechanism, including a 110 crank disc in said transmission mechanism, a motor pulley and a readily removable belt connecting the disc and pulley.

In testimony whereof we have hereunto affixed our signatures.

HOWARD E. CROCKER.
WINFRED W. HARRIS.
